UNITED STATES PATENT OFFICE.

ELIZABETH W. DE HUFF, OF SANTA FE, NEW MEXICO.

DESIGN FOR A DOLL.

Application filed December 11, 1928. Serial No. 29,222. Term of patent 3½ years.

To all whom it may concern:

Be it known that I, ELIZABETH W. DE HUFF, a citizen of the United States, residing at Santa Fe, in the county of Santa Fe and State of New Mexico, have invented a new, original, and ornamental Design for a Doll, of which the following is a specification, reference being had to the accompanying drawing, forming part thereof.

Fig. 1 is a front elevation,
Fig. 2 is a side elevation, and
Fig. 3 is a rear view of a doll showing my design.

I claim:
The ornamental design for a doll, as shown.

ELIZABETH W. DE HUFF.
